UNITED STATES PATENT OFFICE.

CHARLES WEISS, OF NEW YORK, N. Y.

DESIGN FOR A PLATE OR SIMILAR ARTICLE.

Application filed October 24, 1928. Serial No. 28,612. Term of patent 7 years.

To all whom it may concern:

Be it known that I, CHARLES WEISS, a citizen of the United States, and resident of the borough of Manhattan, city, county, and State of New York, have invented a new, original, and ornamental Design for a Plate or Similar Article, of which the following is a specification, reference being had to the accompanying drawing, forming part thereof, which drawing is a face view of a plate or similar article illustrating my new design.

I claim:

The ornamental design for a plate or similar article, as shown.

CHARLES WEISS.
